UNITED STATES PATENT OFFICE.

RALPH P. TUTTLE, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed January 28, 1924. Serial No. 688,917.

To all whom it may concern:

Be it known that I, RALPH P. TUTTLE, a citizen of the United States, residing at Edgewood Borough, in the county of Allegheny and State of Pennsylvania, have invented certain new and useful Improvements in Railway-Traffic-Controlling Apparatus, of which the following is a specification.

My invention relates to railway traffic controlling apparatus, and particularly to apparatus of the type comprising train carried governing means controlled by energy received from the trackway. More particularly, my invention relates to the trackway portion of such apparatus.

I will describe two forms of trackway apparatus embodying my invention, and will then point out the novel features thereof in claims.

20 In the accompanying drawing, Fig. 1 is a diagrammatic view showing one form of trackway apparatus embodying my invention. Fig. 2 is a view showing a modified form of the apparatus illustrated in Fig. 1 and also embodying my invention.

Similar reference characters refer to similar parts in both views.

Referring first to Fig. 1, the reference characters 1 and 1^a designate the track rails of a railroad over which traffic normally moves in the direction indicated by the arrow. These rails are divided, by means of insulated joints 2, into a plurality of successive sections such as D—E. A track relay here designated by the reference character R with an exponent corresponding to the location, is connected across the rails adjacent the left hand of each track section. Referring particularly to section D—E, relay R^D is supplied with track circuit current from a suitable source of energy such as a track battery G^E connected across the rails adjacent the exit end of the section.

45 Means are also provided for supplying section D—E with an alternating current which, for purposes of explanation, I shall term "traffic controlling" current. As here shown this means comprises a track transformer T^E having its secondary winding 6 connected across the rails and in series with battery G. The supply of energy to the primary winding of transformer T^E will be explained in detail hereinafter.

50 Section D—E is provided, intermediate

its ends with a switch A leading from the main track into a side track H. Associated with switch A is a switch circuit controller F comprising two contacts so arranged that when the switch is normal, that is, in such position as to permit unrestricted traffic movements through section D—E, contact 3—3^b is open and contact 4—4^a is closed. When switch A is in any other position, such as the reverse position wherein it permits traffic to move from the main track into the side track H or vice versa, contact 3—3^b is closed and contact 4—4^a is open.

When switch A is normal, current flows from one terminal B of a suitable source of periodic energy not shown in the drawing, through wire 9, contact 4—4^a of circuit controller F, wire 10, front contact 8 of track relay R^E, wire 11, and primary 7 of transformer T^E, to terminal C of said source. When this circuit is closed traffic controlling current is supplied to the rails of the entire section D—E in series.

When switch A is reversed the contact 4—4^a is open and current then flows from terminal B, through wire 9, impedance 5, wire 10, front contact 8 of track relay R^E, wire 11, and primary 7 of transformer T^E, to terminal C. When switch A is reversed a low resistance shunt is also completed across the rails 1 and 1^a adjacent switch A, this shunt path passing from rail 1^a, through wire 12, contact 3—3^b of circuit controller F, and wire 13, back to rail 1. When these circuits are closed it will be clear that traffic controlling current will be supplied to the rails of section D—E in series between switch A and point E, but the shunt path through contact 3—3^b will limit the flow of such traffic controlling current between switch A and point D.

Let us now suppose that a train is approaching switch A and is to the right of point D. The wheels and axles of this train constitute a second low impedance path in multiple with the contact 3—3^b. The traffic controlling current then traversing the rails 1 and 1^a at switch A, will divide in inverse proportion to the impedances of the two low resistance paths, and if the current traversing the rails to the right of switch A were considerably greater than that necessary to operate the train carried train control devices, it is possible that sufficient cur-

rent might flow in rails 1 and 1^a to the left of switch A, and through the wheel shunt to give a proceed indication on the train even though switch A is reversed. To prevent such an occurrence the current traversing the rails at switch A is reduced by impedance 5 to a value just sufficient to reliably operate the train carried device when the train reaches switch A and while it is in the section between switch A and point E. It will, therefore, be seen that by my invention, the current at switch A is so reduced that when divided between the low resistance path of contact 3—3^b and the rails and the wheels of the vehicle at any point to the left of switch A a stop or low speed indication is given aboard the train at all points between D and A.

The trackway apparatus here illustrated may be used in connection with train carried governing means so arranged that when the train occupies a portion of track which is being supplied with train controlling current of a given value, a proceed indication is received on the train but that when the supply of such current is interrupted, or when the magnitude of such current is below such given value, the train receives a stop indication.

As shown in the drawing the track is unoccupied, relays R' and R^b are energized and switch A is normal. Under these conditions the traffic controlling current is of sufficient magnitude to give a proceed indication on board a train at any point in section D—E. I will now assume that switch A is reversed and that a train is approaching section D—E in the section to the left of D—E. The closing of contact 3—3^b shunts relay R^b which becomes de-energized, thus interrupting the supply of traffic controlling current to the section to the left of point D. At the same time the traffic controlling current in that portion of section D—E between point D and switch A is reduced below the value required to give a proceed indication on board the train by the shunt through contact 3—3^b. The train therefore receives a stop indication throughout the section to the left of point D and in section D—E as far as the switch A.

If a train is proceeding under a proceed indication between the switch A and point E, and the switch is reversed in the rear of the train, no change is made in the indication received by the train since impedance 5 is so proportioned as to permit sufficient current to flow through transformer T^e to give a proceed indication on the train between these two points.

It should be noted that if relay R^e is de-energized, as by the presence of a train in the section to the right of point E, the supply of traffic controlling current to section D—E is interrupted, and a train in such sec-

tion will receive a stop indication irrespective of the position of switch A.

The reason for reducing the electromotive force of transformer T^e when the switch is reversed is that the effectiveness of a shunt can not be depended upon alone to prevent the flow of traffic controlling current in rear of the switch. By reducing the electromotive force of the transformer, and simultaneously closing the shunt at switch A, double precaution is taken to prevent a train in rear of the switch from receiving a proceed indication when the switch is reversed. The shunting path at switch A is increased in effectiveness as the voltage of the transformer T is reduced.

In the modification shown in Fig. 2, an insulated joint 2^a is interposed in one rail 1^a adjacent switch A. A shunt path including wire 12, contact 3—3^a of circuit controller F and wire 14 is closed around this insulation joint only when switch A is normal. Consequently, when the switch is reversed, the rails in the rear of the switch, that is, the rails between D and A, are shunted by contact 3—3^b, and the path through rail 1^a is also opened at contact 3—3^a, thereby still further reducing the possibility of sufficient traffic controlling current reaching the rails in the rear of the switch A to give a proceed indication. The control of transformer T^e is the same as in Fig. 1 and the operation of the apparatus will be understood without further discussion.

One feature of my invention is that if a switch is reversed in advance of a train, the train receives a stop indication, but if a switch is reversed in rear of a train no change is made in the indication transmitted to the train.

Although I have herein shown and described only two forms and arrangements of apparatus embodying my invention, it is understood that various changes and modifications may be made therein within the scope of the appended claims without departing from the spirit and scope of my invention.

Having thus described my invention, what I claim is:

1. In combination, a stretch of railway track, a track transformer having its secondary winding connected across the rails of said stretch, a switch in said stretch, and means for controlling the supply of energy to the primary of said transformer in accordance with the position of said switch.

2. In combination, a stretch of railway track having a switch therein, and means for supplying the rails of said stretch in series with traffic controlling current the magnitude of which is varied according as the switch is in the normal or the reverse position.

3. In combination, a stretch of railway track having a switch therein, a track transformer having its secondary winding connected across the rails of the stretch for supplying traffic controlling current thereto, and means associated with said switch for at times inserting an impedance in series with the primary winding of said transformer whereby the value of said traffic controlling current is reduced.
4. In combination, a stretch of railway track having a switch therein, a track transformer having a secondary winding connected with said stretch for supplying traffic controlling current thereto, an impedance associated with the primary winding to said transformer, and means responsive to the position of said switch for at times short circuiting said impedance.
5. In combination, a stretch of railway track having a switch therein, a track transformer having a secondary winding connected with said stretch for supplying traffic controlling current thereto, an impedance associated with the primary winding of said transformer, and means responsive to the position of said switch for at times short circuiting said impedance, and for at other times completing a path of low resistance between the rails of said stretch.
6. In combination, a stretch of railway track having a switch intermediate the ends thereof, means for applying an alternating difference of potential across the rails adjacent one end of said stretch, and means responsive to the position of said switch for at times decreasing the magnitude of said electromotive force.
7. In combination, a stretch of railway track having a switch intermediate the ends thereof, means responsive to traffic conditions in advance of said stretch for applying an alternating difference of potential across the rails adjacent one end of said stretch, and means responsive to the position of said switch for at times decreasing the magnitude of said electromotive force.
8. In combination, a stretch of railway track having a switch intermediate the ends thereof, means for applying an alternating difference of potential across the rails adjacent one end of said stretch, and means responsive to the position of said switch for at times simultaneously decreasing the magnitude of said electromotive force and completing a path of low resistance across the rails of the stretch adjacent said switch.
9. In combination, a stretch of railway track having a switch intermediate the ends thereof, means for supplying traffic controlling current to the rails of the stretch in series, and means responsive to the position of said switch for at times discontinuing the supply of such current to a portion of the stretch and for decreasing the magnitude of
- said current in another portion of said stretch.
10. In combination, a stretch of railway track having a switch intermediate the ends thereof, means for supplying traffic controlling current to the rails of the stretch in series, and means responsive to the position of said switch for at times discontinuing the supply of such current between said switch and one end of the stretch and for simultaneously decreasing the magnitude of such current between the switch and the other end of the stretch.
11. In combination, a stretch of railway track having a switch intermediate the ends thereof, an insulated joint in one rail adjacent said switch, means responsive to traffic conditions for applying an alternating electromotive force across the rails adjacent one end of the stretch, and a circuit around said joint including a circuit controller responsive to the position of the switch and means responsive to the position of such switch for varying the magnitude of said electromotive force.
12. In combination, a stretch of railway track having a switch intermediate the ends thereof, an insulated joint in one rail adjacent said switch, means responsive to traffic conditions for applying an alternating electromotive force across the rails adjacent one end of the stretch, a circuit controller responsive to the position of said switch, means controlled by said circuit controller for at times short circuiting said insulated joint and for at other times completing a path of low resistance between the rails of the stretch adjacent the switch.
13. In combination, a section of railway track provided with a switch, means for connecting a source of traffic controlling voltage across the rails of said section, and means for varying the magnitude of said voltage according as the switch is in its normal or its reverse position.
14. In combination, a section of railway track provided with a switch, means for connecting a source of traffic controlling voltage across the rails of said section, and means controlled by the position of said switch for at times reducing the magnitude of the voltage applied to the section and closing the path of low resistance between the rails of the section adjacent the switch.
15. In combination, a section of railway track provided with a switch capable of assuming two extreme positions, means for applying a train controlling voltage across the rails of the section, and means effective when said switch is in one extreme position for reducing said voltage.
16. In combination, a section of railway track provided with a switch capable of assuming a normal and a reverse position, means for applying a train controlling volt-

age across the rails of said section, and means effective when said switch is in the reverse position for reducing said voltage.

17. In combination, a section of railway track provided with a switch capable of assuming a normal and a reverse position, means for applying a train controlling voltage across the rails of said section, and means effective when said switch is in the reverse position for reducing said voltage and for closing a path of low resistance across the rails of the section adjacent the switch.

18. In combination, a section of railway track provided with a switch capable of assuming a normal and a reverse position, an insulated joint in one rail of the stretch adjacent the switch, means for closing a shunt around said joint when the switch is in the normal position but not when the switch is in the reverse position, means for applying a train controlling voltage across the rails of the section, and means effective when the switch is in the reverse position to reduce the magnitude of said voltage and to close a path of low resistance between the rails of the section adjacent the switch.

19. In combination, a section of railway track containing a switch, and means controlled by said switch for applying across the rails of said section at the exit end of the section a relatively high traffic controlling voltage when the switch is in normal position and a relatively low traffic controlling voltage when the switch is in the reverse position.

20. In combination, a section of railway track containing a switch, a source of traffic controlling current connected across the rails adjacent the exit end of said section, and means controlled by said switch for decreasing the voltage applied across the rails by said source when the switch is in the reverse position.

21. In combination, a section of railway track containing a switch, a track circuit for said section including a source of track circuit current, and means for supplying the rails of said section in series with traffic controlling current the magnitude of which is varied in accordance with the position of the switch.

22. In combination, a section of railway

track containing a switch, a track circuit for said section including a source of track circuit current, and means for applying across the rails of said section a traffic controlling voltage the value of which varies according to the position of said switch.

23. In a railway traffic controlling system for use with train carried governing means arranged to display a less restrictive or a more restrictive indication according as the track occupied by the train is or is not supplied with train governing current, the combination of a section of track, a switch in said section, and means for applying across the rails of said section a train governing voltage the value of which varies according as the switch is in its normal or its reverse position.

24. In combination, a stretch of railway track divided into a forward and a rear section, a switch in said rear section, a track circuit for each section, and means for controlling the track circuit for the rear section by the track circuit for the forward section and by said switch.

25. In combination, a stretch of railway track divided into a forward and a rear section, a switch in said rear section, a track circuit for the forward section, and a track circuit for the rear section controlled jointly by said forward track circuit and by said switch.

26. In combination, a stretch of railway track divided into a forward section and a rear section, a switch in said rear section, means for supplying track circuit current to the rails of the forward section independently of said switch, and means controlled by said switch for supplying track circuit current to the rails of the rear section.

27. In combination, a stretch of railway track divided into a forward and a rear section, a switch in said rear section, means for supplying track circuit current to the rails of the forward section independently of said switch, and means controlled by traffic conditions in said forward section and by the position of said switch for supplying track circuit current to the rails of said rear section.

In testimony whereof I affix my signature.

RALPH P. TUTTLE.
